[57] CLAIM

The ornamental design for a coffee filter device, as shown.

DESCRIPTION

FIG. 1 is a side elevational view of a coffee filter device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a front elevational view of a coffee filter device showing a second embodiment of my new design;

FIG. 7 is a top plan view thereof;

FIG. 8 is a bottom plan view thereof;

FIG. 9 is a side elevational view thereof; and,

FIG. 10 is a top perspective view thereof.

FIG.1

FIG.2

FIG.3

FIG. 4

FIG. 5

FIG. 6

FIG. 7

FIG. 8

FIG.9

FIG. 10
